(57) **CLAIM**

The ornamental design for a bolo closure bag, as shown and described.

DESCRIPTION

FIG. 1 is a perspective view of the bolo closure bag of the present invention with the bolo cord in a partially loosened position;

FIG. 2 is a front elevational view of the bag with the bolo cord fully tightened around the neck of the bottle;

FIG. 3 is a left-side elevational view thereof;

FIG. 4 is a rear elevational view thereof;

FIG. 5 is a top plan view of thereof;

FIG. 6 is a bottom plan view thereof;

FIG. 7 is a right-side elevational view thereof;

FIG. 8 is a perspective view of the bolo closure bag of the present invention illustrating alternate cord ends with the bolo cord in a partially loosened position;

FIG. 9 is a front elevational view of the bag with the bolo cord of FIG. 8 fully tightened around the neck of the bottle; and,

FIG. 10 is a left-side elevational view thereof.

The broken lines in the figures are directed to environment only and form no part of the claimed design.
